UNITED STATES PATENT OFFICE.

FRANCIS A. HOLTSINGER, OF OTTUMWA, IOWA.

LAUNDRY-MACHINE.

1,310,657.

Specification of Letters Patent. Patented July 22, 1919.

Application filed March 28, 1918. Serial No. 225,311.

To all whom it may concern:

Be it known that I, FRANCIS A. HOLTSINGER, a citizen of the United States, residing at Ottumwa, in the county of Wapello and State of Iowa, have invented certain new and useful Improvements in Laundry-Machines, of which the following is a specification.

This invention relates more in particular to machines for dampening collars and cuffs, and it has for its primary object to provide an efficient machine or apparatus for dampening such articles in a rapid and uniform manner subsequent to their treatment in the "drying room" and previous to being ironed.

The invention further resides in the features of construction and the arrangements and combinations of parts hereinafter described in detail and claimed in a succinct manner, reference being had to the accompanying drawings wherein

Figure 1 is a side elevation of the improved machine in action or operation;

Fig. 2 is a fragmentary, vertical, transverse section thereof; and

Fig. 3 is a detailed view more clearly illustrating the construction of the machine.

Referring more specifically to the drawings, the numeral 1 designates the main frame of the structure embodying horizontal side members 2 and inclined frame members

3. Journalled in a depending bracket extension 4 from the side frame members 2, is a pair of large rollers, preferably wooden, mounted in vertical slots 6 and one being adjustable toward the other through the horizontal adjustment afforded by the yieldable means hereinafter described.

40 A pair of endless aprons 7 are provided, one being passed about each roller 5 and otherwise guided by the guide rolls 8, which are journalled on the inclined frame members 3, to form a receiving, funnel-shaped

45 hopper into which the collars and cuffs are deposited. Each apron is further passed about other guide rolls 9 and beneath the immersing roll 10 and between the squeeze rolls 11, said rolls being suitably journalled

50 in the frame structure to accomplish the desired results. Tanks or trays 12 are arranged adjacent each end of the machine and have the immersing rolls 10 journalled in the sides thereof for directing or guiding the aprons down into the dampening fluid, preferably water, after which the aprons

pass through or between the squeeze rolls 11. In this connection it will be noted that the squeeze rolls are disposed directly above the length of apron passing from the main 60 rollers 5 to the immersing rolls so that the water that is extracted by said squeeze rolls will fall or drop onto said length of apron and be conveyed back to the tanks.

One roll of each pair of coöperating 65 squeeze rolls is journalled in the lower end of an inwardly inclined slot 13 while the companion roll is mounted in a horizontal bearing 14 that embodies a yieldable tensioning means similar to that employed for the large 70 wooden main roller 5.

Each tensioning means comprises a horizontally slidable bearing block or shoe 15 which has a rearward extension 16 guided in a bore 17, in the main frame, and a spring 75 18 also arranged within the bore and bearing against the inner end of said extension 16. The tension of the coiled spring 18 is adjusted by the compression screw 19 that is threaded through the outer end wall of the 80 bore 17. Thus, the tension of the spring and the pressure between the coöperating rolls and rollers may be varied to a greater or lesser extent as the compression screw is advanced or retracted. Consequently, the 85 degree of dampness given the collars and cuffs may also be varied by the pressure between the rollers 5.

In operation, the collars and cuffs are fed from the drying room on a series of hooks 90 20 of an endless conveyer 21 and are dislodged from said hooks by a trip 22 directly over the downwardly converging aprons between which they pass, to be dampened, into a suitable receptacle 23. The articles are 95 then removed from the receptacle and ironed.

The degree of dampness imparted to the collars and cuffs may be varied by increasing the tension on the squeeze rolls as well as 100 varying the pressure between the pressure rollers. Thus the invention is rendered efficient and practical and at the same time possesses simplicity and durability in construction.

105

What is claimed is—

1. A dampening machine for laundry use, comprising a frame having horizontal side frame members and a pair of upwardly divergent frame members leading from each 110 side member, a series of guide rollers journalled in each upwardly divergent frame

2
member, an endless apron passing over each series of rollers to define with the companion apron a wide hopper tapering toward the bottom, and coöperating pressure rollers arranged within the endless aprons and adjustable to vary the pressure on the sides of the discharge opening at the bottom apex of the hopper.

2. A laundry machine comprising a main frame, a pair of main rollers journaled thereon, spaced series of guide rolls extending upwardly from the rollers in divergent relation, and a pair of endless aprons passing about the rolls and rollers.

3. In a dampening machine for laundry use, a frame, upwardly divergent series of rollers journaled therein, endless aprons passing over the series to define a hopper having downwardly convergent sides, yieldably separable pressure rollers closing the bottom apex of the hopper thus defined, a coöperating pair of squeeze rolls for each

apron arranged behind the upwardly divergent portion of said apron, and a liquid-containing tank for each apron arranged beneath and outwardly of the respective pair of squeeze rolls, said apron passing beneath the latter toward the tank. 25

4. In a dampening machine for laundry use, a frame, upwardly divergent series of 30 rollers journaled therein, endless aprons passing over the series to define a hopper having downwardly convergent sides, yieldably separable pressure rollers closing the bottom apex of the hopper thus defined, a 35 coöperating pair of squeeze rolls for each apron, arranged behind the upwardly divergent portion of said apron, one roll of each pair being journaled in an inclined slot in the frame and the companion roll being 40 mounted for variable resilient pressure thereagainst.

FRANCIS A. HOLTSINGER.
